CLAIM

The ornamental design for a camping chair, as shown and described.

DESCRIPTION

FIG. 1 is a top perspective view of my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view thereof, taken from the encircled portion 9 in FIG. 1; and,

FIG. 10 is an enlarged view thereof; taken from the encircled portion 10 in FIG. 2.

The dash-dash broken lines in the drawings depict portions of the camping chair and form no part of the claimed design. The dash-dot-dash broken lines in the drawings are included to indicate a partially enlarged view and form no part of the claimed design.

1 Claim, 10 Drawing Sheets
